FIG. 5

FIG. 2

FIG. 1

FIG. 3

FIG. 4

FIG. 6

FIG. 7

FIG. 1 is a front elevation of a combined writing implement and holder;

FIG. 2 is a side elevation of the combined writing implement and holder as shown in FIG. 1;

FIG. 3 is a side elevation of the combined writing implement and holder from the other side of that shown in FIG. 2;

FIG. 4 is an exploded rear elevation of the combined writing implement and holder shown in FIG. 1;

FIG. 5 is a top plan;

FIG. 6 is a bottom plan; and

FIG. 7 is an exploded front perspective view of another embodiment of the combined writing implement and holder shown in FIG. 1 wherein the ribbing or grooving has been omitted from the writing implement and a holder of slightly different configuration and appearance is disclosed. The back of the holder which is not seen in FIG. 7 is identical to the back of the holder shown in FIG. 4.

I claim:

The ornamental design for a combined writing implement and holder, substantially as shown and described.
